To all whom it may concern:

Be it known that I, Benjamin Cutler, a citizen of the United States and residing at No. 4123 Bedford Avenue, Borough of Brooklyn, county of Kings, city and State of New York, have invented a new, original, and ornamental Design for a Dress or Similar Article, of which the following is a specification, reference being had to the accompanying drawing, forming part thereof.

I claim:

The ornamental design for a dress or similar article, as shown and described.
